UNITED STATES PATENT OFFICE

GEORGE A. REEVE, OF ASHLAND, KENTUCKY, ASSIGNOR TO THE AMERICAN ROLLING MILL COMPANY, OF MIDDLETOWN, OHIO, A CORPORATION OF OHIO

GUIDE

Application filed July 22, 1929. Serial No. 380,149.

My invention relates to guiding mechanism that will deliver rolled sheets to a rolling mill, or from one mill to another. The object of my invention is to provide means for delivering the sheets in such a manner that the sheets will enter the mill squarely, i. e., so that the axis of the sheets will always be substantially perpendicular to the axis of the rolls, whereby skewed ends are prevented from forming while the sheets are passing through the mill.

It is another object of my invention to provide a fixed side guide for a sheet against which the sheet will be held by a positive mechanical means while passing from one mill to another.

Still another object of my invention is to provide a means for holding the sheet in contact with the fixed guide, which means will adjust itself for any irregularities occurring along the edge of the sheet.

A further object of my invention is to provide a resilient pressure device for holding the sheet against a fixed guide in a line perpendicular to the axis of the mills.

Another object of my invention in one aspect is the provision of driving means for the said pressure means, so that the sheets do not tend to bind, warp, or stick in the guides.

These and other objects of my invention which will be pointed out hereinafter or will be apparent to one skilled in the art upon reading these specifications, I accomplish by that certain construction and arrangement of parts of which I shall now describe an exemplary embodiment and a modification, reference being had to the drawings which accompany these specifications.

40 In the drawings:—

Figure 1 is a side elevation of the pressure means comprising a double drum, which is the preferred form of my invention.

Figure 2 is an end elevation of the spring actuating means for the double drum pressure means.

Figure 3 is a top plan view of the double drum and support with their gear arrangements.

50 Figure 3a is part of an end elevation show-

ing the double drum holding a sheet against the fixed side guide.

Figure 4 is an end elevation of a spring drum holding means, together with the conveyor and side guide, with parts in section.

Figure 5 is a side elevation of a single drum pressure means.

Figure 6 is a top plan view diagrammatically illustrating two mills, conveyor and guide means in position.

Figure 7 is a diagrammatic plan view of two mills with conveyor and double drum pressure means in place.

I have shown two types of drums for holding the sheets in proper alignment with relation to the rolls of the mill. The double drum type as illustrated in Figures 1, 2, 3 and 3a, is a preferred form; and the single drum illustrated in Figures 5 and 6 is a modification thereof, the action of both being the same in principle.

I have shown a chain conveyor 1 having a framework 2, which is used to deliver sheets into a mill or between two mills. There may be two continuous chains 3, free to slide in channel iron guides 4, which keep the chains running in a straight line. The tops 5 of these chains extend above the legs 6 of the channels, so that a sheet of metal 7, to be conveyed, may come in contact with them and be carried along. The chains are driven by means of sprockets 8 indicated in Figure 6, and are guided by means of the sheaves 9 fixed to an idler shaft 10 rotatively mounted in the bearings 11 on the side frames of the conveyor.

One of the chains passes over a sprocket 12 on a shaft 13 which is mounted in a bearing 14 on the side frame of the conveyor. This shaft is held from lateral thrust by means of a collar 15 and the sprocket 12. It is the main drive shaft for the pressure drums that hold the sheet of metal against a fixed side guide 16. The surface 16a of this guide is in a line perpendicular to the mills and is the means for keeping the sheet in proper alignment while passing to and entering between the rolls 65 and 68 of the mills (see Fig. 7).

The other end 18 of the shaft 13 is rotatively mounted in a bearing 19 which is part of

the drum supporting bracket 20. There is a key slot 21 in this shaft in which a key 21, fixed in a bevel gear 22, is free to slide. This arrangement permits the movement of the bracket toward or away from the frame of the conveyor while keeping a positive driving relation between the shaft 13 and the bevel gear 22.

5 The bevel gear 22 meshes with and drives another bevel gear 23 and also a vertical shaft 24, to which the said gear is attached. This shaft 24 is rotatively mounted in a bearing 25, also part of the drum supporting bracket.

10 15 The lower half 26 of a saw tooth clutch is fixed to the shaft 24 and drives the drum 27 through another half 28. This clutch arrangement is provided to allow slippage between the pressure drum drive and the conveyor chain if a sheet should become jammed 20 between the fixed guide and the surface 29 of the drum.

25 My single drum arrangement consists of a hub 30 which is rotatively mounted on the shaft 24 and is driven by the ratchet clutch as has been explained. The outer ring 31 of this drum is supported on the hub 31a by means of conical spring spokes 32, which are free to expand and contract when a sheet 30 pushes against the surface 29. This ring has a flange 33 that supports the extending edge 34 of a sheet of metal in contact with it. Normally, the drum will be positioned so as to be in contact with slight pressure against 35 the edge of a sheet of metal. If there are any irregularities, the drum will follow them because of the action of the springs, and thereby keep the sheet in contact with the guide 16.

40 In order to move the drum into contact with a sheet, i. e. to set the device for guiding a new size of sheet, I have provided a screw 35, one end 36 being rotatively mounted in a bearing 37 fixed to the side frame of the conveyor, and the other end 38 also rotatively mounted in another bearing 39 fixed to an I beam 40. The screw 35 is kept from lateral movement by means of the thrust collars 41, and may be rotated by means of a handle placed on its squared end 42. The screw operates in the threaded boss 43 of the drum supporting bracket, and thereby may be caused to move the bracket.

45 Extending from the sides of the threaded boss are wings 44 which are free to slide in the channels 45 which guide the drum supporting bracket. Thus, the boss is prevented from rotating about the drum main drive shaft 13.

50 55 60 I have shown two forms of pressure means for holding the sheets against the guide, the one just described, and a preferred form having two drums. For the latter form the driving mechanism and support are the same, 65 including the vertical shaft 24a. In Figure 1

the drum shown in section is provided with springs, as shown in Figure 4, the view in Figure 1 being at right angles to the springs. In the two-drum type, however, I have provided a supporting plate 46, which is rotatively mounted upon the shaft 24, and supports two drums 47 and 47a, and gears to be described.

65 70 75 A spur gear 48 is keyed to the shaft 24, and meshes with two idler spur gears 49 and 49a. These in turn drive two additional spur gears 50 and 50a arranged to drive the two drums in the same direction (clockwise in the figures). The gears 49 and 49a are rotatively mounted on studs 51 and 51a upon the supporting plate 46. The gears 50 and 50a are keyed to sleeves 52 which are rotatively mounted on studs 53 on the supporting plate. The sleeves in turn are fixedly mounted in the hubs 54 of the drums and support the outer 80 85 ring of the drums through spring spokes, as previously described.

80 85 90 Extending from the supporting plate is an arm 55 which has an upwardly extending portion 56 against which, on both sides, 95 springs 57 and 57a bear. These springs return the supporting plate to normal set position after it has been moved therefrom by the action of the irregularities in the edge of the sheets upon the drums. The springs are held between two spring plates 58 and 58a which are rigidly fastened to an arm 59 upon the supporting bracket 20. This arm is stationary and does not move with the supporting plate 46. A stud 60 passes through holes 61 in the spring plates and is held in a fixed position by the nuts 62 and 62a. In order to regulate the tension of the springs, I have provided threads 63 and 63a for nuts 64 and 64a which screw against the springs and hold them in the desired compressed condition.

95 100 105 The normal setting of the supporting plate 46 is such that the forward drum 47 is somewhat further away from the guide 16 than the rear drum 47a. When a sheet 7 has come through the rolls 65, it will be picked up by the conveyor 3 and carried toward rolls 68, possibly somewhat askew. The forward drum 47 will engage the sheet end first and will move it over toward the guide 16, at least to a position where it may be engaged by the rear drum 47a and resiliently pressed with its edge squared against the guide 16. Thus, a proper automatic feeding of the sheet into the rolls 68 is ensured.

110 115 120 Various modifications may be made in my invention without departing from the spirit thereof.

125 Having thus described my invention, what I claim as new and desire to secure by Letters Patent, is:—

130 135 140 1 In combination with a conveyor for moving metallic sheets, a fixed guide and resilient means for holding a metallic sheet in contact with said guide during its forward

- travel, said means comprising a rotative drum and driving means therefor.
2. In combination with a conveyor for moving metallic sheets, a fixed guide and resilient means for holding a metallic sheet in contact with said guide during its forward travel, said means comprising a rotative drum and driving means therefor, and means for adjusting the position of said drum with reference to said guide. 5
3. In combination with a conveyor for moving metallic sheets, a fixed guide and resilient means for holding a metallic sheet in contact with said guide during its forward travel, said means comprising a movable support, and a resilient member rotatably mounted thereon, and having a rim for engaging the edges of said sheets. 10
4. In combination with a conveyor for moving metallic sheets, a fixed guide and resilient means for holding a metallic sheet in contact with said guide during its forward travel, said means comprising a movable support, and a resilient member rotatably mounted thereon, and having a rim for engaging the edges of said sheets, driving means for said resilient member, a source of power therefor, and means maintaining an operative connection between said source of power and said driving means irrespective of the movement of said support. 15
5. In combination with a conveyor for moving metallic sheets, a fixed guide and resilient means for holding a metallic sheet in contact with said guide during its forward travel, said means comprising a movable support, a supplementary resiliently mounted support movable with reference to the first, and a plurality of rotatably mounted members on said supplementary support adapted to engage said sheets and hold them against said guide. 20
6. In combination with a conveyor for moving metallic sheets, a fixed guide and resilient means for holding a metallic sheet in contact with said guide during its forward travel, said means comprising a movable support, a supplementary resiliently mounted support movable with reference to the first, and a plurality of rotatably mounted members on said supplementary support adapted to engage said sheets and hold them against said guide, one of said members being located at a greater distance from said guide, so as to effect a preliminary placing of said sheets. 25
7. In combination with a conveyor for sheets of metal between rolling mills, a fixed guide, spring mounted drums, gears for driving said drums in the same direction, a rotatable plate for mounting said drums and gears, and means for positioning said plate with reference to said guide, said means comprising a movable bracket upon which said plate is mounted, and spring means holding said plate in a normal position on said bracket. 30
8. In combination with a conveyor for sheets of metal between rolling mills, a fixed guide, spring mounted drums, gears for driving said drums in the same direction, a rotatable plate for mounting said drums and gears, and means for positioning said plate with reference to said guide, said means comprising a movable bracket upon which said plate is mounted, and spring means holding said plate in a normal position on said bracket. 35
9. In combination with a conveyor for sheets of metal between rolling mills, a fixed guide, spring mounted drums, gears for driving said drums in the same direction, a rotatable plate for mounting said drums and gears, and means for positioning said plate with reference to said guide, said means comprising a movable bracket upon which said plate is mounted, and spring means holding said plate in a normal position on said bracket, and means for driving said drums, said means comprising a sliding driving connection permitting the motion of said bracket. 40
10. In combination with a conveyor for sheets of metal between rolling mills, a fixed guide substantially perpendicular to the axis of the rolls of the second mill, drums for holding sheets against said guide, resilient supports for said drums, driving means for said drums, and means for positioning said drums relative to the edges of said sheets. 45
